G. W. DOVER

SPLINING TOOL

Filed Dec. 24, 1924

INVENTOR:

George W. Dover
By Percy H. Plant
ATTORNEY

UNITED STATES PATENT OFFICE.

GEORGE W. DOVER, OF LONGMEADOW, RHODE ISLAND, ASSIGNEE TO THE MONTGOMERY TOOL AND MACHINERY COMPANY, A CORPORATION OF RHODE ISLAND.

SPLINING TOOL.

Application filed December 24, 1924. Serial No. 757,916.

This invention relates to a splining tool which is adapted for use in connection with shapers, planers, and the like for cutting grooves for keys and for other work of like character.

One object of the invention is to provide a device of this character wherein the cutter may be readily adjusted and secured in a variety of angular positions relative to the holder.

Another object of the invention is to provide an improved cutter and holding means therefor, whereby clearance for the cutter is provided and proper location of the same relative to the work is insured at all times, as well as the maintenance of a standard width of cut at all times.

A further object of the invention is to provide a bit having two cutting edges whereby considerable time and trouble is avoided as the cutter may be used twice without regrinding.

Other objects and advantages of the invention relate to certain improved details of construction and improved methods of operation as will be more fully set forth in the detailed description to follow.

In the accompanying drawings which form a part of this application:

Fig. 1 is a front elevation of my novel tool.

Fig. 2, a side elevation of the same,

Fig. 3, a top plan view,

Fig. 4, a section on line 4—4 of Fig. 3,

Fig. 5, a section on line 5—5 of Fig. 3, and,

Figs. 6 and 7, sections on lines 6—6 of Fig. 2, and 7—7 of Fig. 3 respectively.

Like reference characters indicate like parts throughout the several views.

In detail my tool comprises a supporting arm or shank 7 adapted to be carried by the tool post of a shaper or planer. The shank 7 has upon its end an enlarged integral head 8 having a cylindrical extended portion 9. The head and extension have a bore 10 which is provided with broad shallow internal threads 6, for the reception of a tool bar 11 provided with external threads 12 engaging the threads 6 of the bore whereby the bar 11 is located at right angles to the shank 7. This bar is mounted for longitudinal and angular movement and may be clamped in any longitudinal or angular position by means of a binding pin 13 located

in an opening 14 in the head 8 communicating with the bore 10 and at right angles thereto. The bolt comprises a body 15, a head 16, and a threaded end portion 17 upon which is a binding nut 18 engaging the washer 19 resting against the head. The side of the bolt is provided with an arcuate channel or recess 20 to receive the periphery of the rod 11. Tightening the clamping nut serves to bind the bolt and the rod in any desired position of the latter.

The tool bar is provided with an enlarged cylindrical head 22 having a diametrical opening 23 extending therethrough. The exterior of the head is recessed at one end of the bore to form a rectangular seat or recess 24. Loose in the opening 23 is a cylindrical plug or bushing 26 provided at one end with a rectangular flange 27 registering in the recess 24 whereby the bushing is maintained in proper position and held against turning. The end face of the bushing and the flange are each convex to conform to the exterior contour of the head 22. The bushing is provided with a longitudinally disposed open channel or slot 31 flat at the bottom, as at 32 and diverging outwardly at its sides, as at 33. Slidable in the slot 31 is a cutting tool 34 longer than the diameter of the head and conforming transversely with the shape of the slot having tapering side faces 36, so that its front face 37 is broader than its rear face 38 and parallel therewith. The end faces 39 of the cutting tool are inwardly inclined rearwardly from the broad cutting face 37. The head 22 has in its end a longitudinally disposed threaded aperture 41 extending to the channel 31 and adapted to receive a threaded binding screw 42 having a squared head 44 and which is adapted to clamp the bit against movement.

The tapering sides of the cutting tool insure it a firm seating in the bushing and provides a clearance for the same in cutting. The removable character of the bushing 26 enables its being hardened to resist wear by the cutting tool.

In the operation of my improved tool the shank 7 is placed in the tool post and clamped in position the tool bar 11 is threaded into the head 8 to the desired extent and so that the cutting tool 34 will occupy the proper angular position for cutting. The nut 18 is then tightened to clamp

the tool bar firmly in position. The cutting tool 34 is then adjusted properly to give the desired depth of cut and clamped in that position by the binding screw 42.

5 The rectangular flange 27 of the bushing 26 positively holds the bushing in position so as to insure proper operation of the cutting tool 34 at all times, while the inclined sides of the cutting tool insure a firm seating of the tool and provide proper clearance on both sides. The cutting tool having two cutting edges is reversible and one grinding only is therefore necessary for two cuttings such as would ordinarily necessitate two grindings.

15 What I claim is:—

1. In a device of the character described, a supporting arm provided with a threaded opening extending transversely therethrough, a tool bar provided with a transverse opening adjacent to one end thereof and having a threaded portion insertable within the threaded opening in said arm and adjustable both angularly and longitudinally with respect to said arm, means for clamping said bar to said arm in any one of its adjusted positions, a cutting tool mounted in the transverse opening in said tool bar and adjustably longitudinally within the opening in said tool bar, and means for clamping said cutting tool to said tool bar in any one of its adjusted positions relative thereto.

2. In a device of the character described, a supporting arm provided with a threaded opening extending transversely therethrough, a tool bar provided with a transverse opening adjacent to one end thereof and having the opposite end thereof threaded for insertion within the threaded opening in said arm, said tool bar being adjustable both angularly and longitudinally with respect to said arm, means for clamping said tool bar in said arm in any one of its adjusted positions, a bushing mounted in the transverse opening in said tool bar and provided with a recess for the reception of a cutting tool, a cutting tool mounted in the recess in said bushing and extending transversely of said tool bar and adjustable longitudinally in said recess, and a clamping screw threaded in said tool bar and bearing against said cutting tool to clamp said cutting tool to said tool bar in any one of its adjusted positions.

3. In a device of the character described, a tool bar provided with a transverse opening extending therethrough and having an

angular recess communicating with said opening, a bushing seated in said opening having an angular portion fitting in said recess and provided with a slot for the reception of a cutting tool, and a cutting tool supported by said bushing and mounted in the transverse opening in said tool bar.

4. In a device of the character described, a tool bar provided with a circular opening extending transversely therethrough and having an angular recess communicating with said opening, a bushing having a circular portion fitting within said circular opening and an angular portion fitting within the angular recess and provided with a longitudinal slot for the reception of a cutting tool, and a cutting tool supported by said bushing and mounted in the transverse opening in said tool bar.

5. In a device of the character described, a tool bar provided with an opening extending transversely therethrough, a bushing fitting in said opening and having a slot in one side thereof, the walls of said slot being inclined inwardly, and a cutting tool having the sides thereof inclined inwardly to fit within the slot in said bushing, a binding screw axially mounted in said tool bar and engaging said cutting tool for clamping said cutting tool within the slot in said bushing and holding said cutting tool and bushing in the opening in said tool bar.

6. In a device of the character described, a tool bar provided with a circular opening, a bushing fitting within the opening in said bar provided with an angular head and having a groove for the reception of a cutting tool, a cutting tool seated in said groove, and a shoulder on said tool bar adapted to engage the angular head of said bushing to hold the bushing and cutting tool against rotation.

7. In a device of the character described, a tool bar provided with a transverse circular opening, a bushing fitting within the opening in said bar provided with a groove for the reception of a cutting tool and having an angular head, a cutting tool seated in said bushing, a shoulder on said tool adapted to engage the angular head of said bushing, and a screw threaded in the end of said tool bar and engaging the cutting tool to hold said cutting tool and bushing in fixed position.

In testimony whereof I have affixed my signature.

GEORGE W. DOVER.
